DEVICE EMPLOYING FLUID ELECTRODES

Isay Balinkin and Dare A. Wells, Cincinnati, Ohio

Application April 7, 1932, Serial No. 603,833

1 Claim. (Cl. 176—42)

Our invention applies in one of its aspects to the general class of electrical devices employing electrodes or contact members of fluid material, such as mercury, and in this class are included, but without limitation, the class of devices known as mercury switches, which have a broad field of usefulness in the electrical art. Other phases of our invention relate to particular classes of such devices, and the specific embodiment employed herein for purposes of illustration is a mercury vapor arc device.

It is an object of our invention to provide means in devices of the class referred to for maintaining a body of liquid conductive substance in contact with a suitable terminal so that said body of liquid may serve as a contact member, electrode terminal, or the like, under substantially all conditions of use of the device. Consequently, it is an object of our invention to provide means in an electrical device of the character described for maintaining a portion of mercury, or the like, in position in association with a conductor, irrespective of the position, location, or condition of the remainder of a body of liquid conductive substance in the device.

It is also an object of our invention to provide means whereby terminal members may be less subject to deleterious conditions in the use of the device.

Yet another object of our invention is the provision of improvements in mercury vapor arcs, as will hereinafter be more fully described.

These and other objects of our invention which will be set forth hereinafter or will be apparent to one skilled in the art upon reading these specifications, we accomplish by that certain construction and arrangement of parts of which we shall now describe the aforesaid exemplary embodiment.

The drawing shows:

In Fig. 1 a side elevation of a mercury vapor lamp embodying our invention.

Fig. 2 is a front elevation thereof.

Hitherto in mercury vapor arc lamps, and in other types of electrical devices employing liquid electrodes or terminal agents, difficulty has been experienced in maintaining a body of the liquid continuously in contact with the necessary terminal elements of the device. Thus it has been the practice in lamps to seal into an envelope of pyrex, glass, quartz, or the like, terminal wires or elements of tungsten, or other refractory metal, with or without an intermediate sealing substance. In the operation of the device, it is desired to keep a pool of mercury in

constant contact with the terminal element, so that the mercury itself and not the terminal element will serve as the actual electrode. In arc lamps of the kind which are started by tilting, the tilting operation very frequently removes the mercury from one of the terminal elements, which upon the initial striking of the arc becomes the actual electrode, and is subjected for a short period to exceedingly high temperatures. This is disadvantageous in two respects: First, that some of the metal of the terminal is volatilized and mirrors out upon the walls of the vessel, thereby cutting down the light transmitted therethrough, and secondly, because the heat developed in the terminal itself is likely to disrupt the seal and cause the vessel to fail. Somewhat the same problem, encountered in devices of the mercury switch class, has been solved by locating the terminals in wells which are always kept full of mercury, but this in turn limits the angle through which the switch element may be tilted during the operation thereof, and consequently limits the use of the switch.

A salient object of our invention comprises means for maintaining a body of mercury, or the like, in contact at all times with the terminal elements, quite irrespective of the disposition of the remainder of the liquid substance. To this end we locate our terminal elements in portions of the vessel which are larger than said elements so that the liquid may lie thereabout, but we provide between such portions and other or working portions of the device, a constriction of such character as will maintain the mercury in the space aforesaid, while permitting sufficient volume of mercury to exist in the constriction to provide a device of low electrical resistance.

In Figs. 1 and 2, we have shown the mercury vapor lamp consisting of a straight tube 1 and a branch tube 2. The upper portion of the straight tube indicated at 3 is adapted to serve as a condenser, while the lower portion 4 serves as one of the terminals of the device and may be of shorter effective length than the branch tube 2. The terminals in this device are sealed into the ends of the portions 4 and 5, and are indicated at 6 and 7, which may be thought of as wires of tungsten, or the like, sealed into the envelope, with or without intermediate sleeves. The envelope may, of course, be of pyrex, quartz, or any other suitable material for the purpose desired, and the sealing in of the terminals may be done by any of the known suitable methods. The inner ends of the terminals 6 and 7 lie within spaces indicated at 8 and 9, which are adapted to be

filled with mercury, or other liquid conductive agent as shown. Ahead of these spaces we have formed in the envelope, constrictions comprising thickened portions 10 and 11 in the envelope, and 5 having a constricted passageway 12 and 13. The exact dimensions of these constricted passageways may vary over considerable limits. The factors which bear thereon primarily are: that the passageways shall be small enough so that the 10 surface tension of the mercury or other liquid conductive agent employed will be sufficient to hold in place the body thereof within the spaces 8 and 9 when the tube is tilted so as to send the remainder of the liquid therein into some other 15 portion; but they should not be so small in cross-sectional area as to create an unduly high resistance for the passage of current through the conductive liquid in the said constricted openings. In an ordinary small mercury vapor lamp 20 these constricted passageways may be of the order of $\frac{1}{2}$ of an inch in diameter, and will give excellent results, but these dimensions are not limiting.

When the tube or lamp is tilted, the mercury 25 or other conductive liquid breaks at the said constricted passageways so that under all ordinary conditions of use the liquid in the spaces 8 and 9 remains in position, and at all times completely covers the terminals 6 and 7.

30 In the device of Fig. 1 a tilting in any direction, followed by a return of the device so that the tube 1 is substantially vertical, will result in a starting of the arc. For example, the device may be tilted first in a counter-clockwise direction 35 so that the body of mercury 14, lying above the constricted passageway 13, will spill over into the condenser tube 3 through the rounded neck 15. Then if the tube is tilted in a clockwise direction the excess mercury will spill back through 40 the neck 15, forming instantaneously a continuous stream between a body of mercury 16 in the portion 4 and the body of mercury 14. Equilibrium is attained when the bodies 16 and 14 are 45 in the position shown, the depth of the body 16 being maintained by gravity at the lower inside surface of the neck 15. The arc, of course, is maintained between the body 16 and the body 14, through the neck 15, and when the lamp is used 50 for technical purposes, light is ordinarily taken from that portion of the column of the arc which exists in the straight tube portion 2. When, due to the heat of the arc, the mercury is evaporated either from the body 14 or from the body 16, the 55 vapor passes up into the portion 3, where it condenses into liquid mercury again, dropping down to join the body 16. As this body increases in bulk, any excess of the mercury will spill over through the neck 15 to maintain the level of the body 14.

60 The type of arc lamp which we have illustrated in our drawing is a type suitable for direct current operation, and as such it makes no difference which terminal of the arc is positive. The 65 shape which we have given our device gives new and remarkable results, and it is possible to start the lamp not only by tilting it in the direction aforesaid, but also by tilting it in substantially any other direction. Thus the arc may be started 70 equally as well by tilting the tube out of the plane of the paper as illustrated, and then returning it to an upright position, or, if tilted in the plane of the paper, it may be tilted initially in a clockwise direction, and then returned in a 75 counter-clockwise direction to upright position.

Another advantage of our electrode construction as shown is that whereas in lamps in the past there has been a disadvantageous transmission of heat from the mercury at the arcing surface to the terminal device, both by conduction and by convection, in our device conduction is greatly minimized by the relatively small cross section of the mercuric body in the constricted passageways 12 and 13, and convection currents can be effective only above and below these passageways. In operation, the terminal portions 10 of our lamp stay relatively quite cool, usually not uncomfortably warm to the fingers, whereas great heat is developed at the surface of the bodies 14 and 16, and therebetween. In our construction the chief way in which heat is transmitted to terminal 6 is by direct radiation, since conduction and convection through the mercury have been decreased to negligible amounts, and the heat conductivity of glass, quartz or other 20 material forming the envelope, is quite small.

It will be seen that by a very simple and economical construction which does not involve complicated problems of glass blowing, we have succeeded in producing a device in which the arc 25 is very easily started, and in which the terminals are at all times protected by an overlying body of the conductive liquid. We claim not only improvements in mercury vapor arc construction, or the like, but also our novel terminal or electrode construction, since it will be obvious that 30 it is applicable to other devices than the exemplary embodiment herein disclosed. It will be applicable, for example, to mercury switches and the like, and will have the advantage of maintaining a body of mercury at all times in contact with the terminals. In this way not only may the permissible angle of tilting of the switch be increased if desired to 360 degrees, but also the 35 construction of mercury switches may be greatly simplified. A straight tubing with one of our terminal constructions at either end and a sufficient body of mercury therebetween to bridge the gap between the terminal constrictions when the tube is substantially in horizontal position, 40 may be tilted through any angle desired, or may be mounted directly upon a rotating shaft to serve as a current interruptor, and will be as accurate as and more positive in its action than mercury switches heretofore constructed.

Our arc lamp has specific advantages in that the arc is not struck through or around complicated glass constructions which are likely to fuse or change their shape during the operation of the device, and in that the lamp lasts longer, 55 and the arc stays lit throughout the entire period of the action of the electric current without interruption.

Having thus described our invention, what we 60 claim as new and desire to secure by Letters Patent, is:

In a mercury vapor arc lamp, an envelope comprising a longer and a shorter leg, each having a terminal connection at one end, the other end of the longer leg joining the other end of 65 the shorter leg by a portion regularly curved on a substantially uniform radius of ample length, said envelope also comprising a condensing portion extending from said other end of said shorter leg in substantial axial alignment with said 70 shorter leg, from the place of junction of the longer leg with the shorter leg, said longer leg and said shorter leg and said condensing portion all being of substantially the same diameter, except that said condensing portion at its free end is 75

enlarged, said shorter leg comprising, for a distance substantially half of its length between its terminal connection and the junction of the longer leg, a chamber in which mercury is to be 5 trapped adjacent to the terminal connection, and said longer leg having a chamber of length substantially equal to the chamber in the shorter leg to trap mercury around the terminal connection of said longer leg, said envelope containing 10 a quantity of mercury sufficient to fill said chambers, to fill the remainder of the shorter leg from its chamber to the junction of the longer leg with the shorter leg, and to fill the chamber of the longer leg and to occupy said longer leg 15 exteriorly of the chamber thereof to a length substantially equal to that of extent from the

chamber of the shorter leg to said junction, and the two legs and said condensing portion of said envelope having their axes in substantially a single plane, said chambers for trapping the mercury around the terminal each being defined by 5 modification of the walls of the respective leg of the envelope which forms a passage between the chamber and the remainder of the leg which is so constricted that when the lamp is inverted or tilted to any degree, a substantial proportion 10 of the mercury is trapped during the inversion or tilting within the chamber around the respective terminal.
